CLAIM

The ornamental design for an “input/output terminal for computer,” as shown and described.

DESCRIPTION

FIG. 1 is a right front perspective view of an input/output terminal for computer showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevational view thereof; and,

FIG. 7 is a left side elevational view thereof.
